UNITED STATES PATENT OFFICE.

HERRMAN SIMONS, OF CINCINNATI, OHIO.

DESIGN FOR A FISH-BOWL AND SUPPORT.

51,433.

Specification for Design.

Patented Oct. 23, 1917.

Application filed July 13, 1917. Serial No. 180,451. Term of patent 7 years.

To all whom it may concern:

Be it known that I, HERRMAN SIMONS, a citizen of the United States, and a resident of the city of Cincinnati, in the county of Hamilton and State of Ohio, have invented a new, original, and ornamental Design for Fish-Bowls and Supports, of which the following is a specification, reference being had

to the accompanying drawing, forming part thereof.

The figure is an elevation of the support for a fish globe.

I claim:

The ornamental design for a fish bowl and support, as shown.

HERRMAN SIMONS.
